UNITED STATES PATENT OFFICE

106,899

DESIGN FOR A COMBINED BUREAU AND WARDROBE

Floyd H. Newmaker, Warren, Pa.

Application September 10, 1937, Serial No. 71,559

Term of patent 3½ years

To all whom it may concern:

Be it known that I, Floyd H. Newmaker, a citizen of the United States, residing at Warren, in the county of Warren and State of Pennsylvania, have invented a new, original, and ornamental Design for a Combined Bureau and Wardrobe, of which the following is a specification, reference being had to the accompanying drawings, forming part thereof.

I claim:—

The ornamental design for a combined bureau and wardrobe, as shown.

FLOYD H. NEWMAKER.
